UNITED STATES PATENT OFFICE.

FRANCIS W. RANDALL, OF TEKONSHA, MICHIGAN.

TRIPPING DEVICE FOR HARVESTERS.

SPECIFICATION forming part of Letters Patent No. 239,982, dated April 12, 1881.

Application filed December 2, 1880. (No model.)

To all whom it may concern:

Be it known that I, FRANCIS W. RANDALL, of Tekonsha, in the county of Calhoun and State of Michigan, have invented a new and useful Improvement in Trips for Harvester-Rakes, which improvement is fully set forth in the following specification and accompanying drawings.

The object of my invention is to produce a new device for tripping the rake-switch of a grain-harvester for the purpose of controlling the operation of the rakes; and it consists in parts and devices hereinafter fully explained, and more particularly pointed out in the claims.

Figure 1, Sheet 1, of the drawings shows, in plan, an ordinary rake-cam of a harvester with my tripping device attached. Fig. 2 shows, drawn to a larger scale, a side elevation of the tripping device, with portions of the cam and reel-rake shaft. Fig. 3 is an end view of the latter figure, viewed as indicated by the arrow of said Fig. 2. Fig. 4 is a side elevation of the switch, with its arm and other attachments, viewed as indicated by the arrow in Fig. 1. Fig. 5, Sheet 2, is a side elevation of the similar parts shown in Fig. 2, viewed in an opposite direction; Fig. 6, an enlarged view of several parts shown in Fig. 5, viewed as indicated by the arrow in the latter figure; Fig. 7, a side elevation of several of the parts shown in Fig. 2, viewed from the same standpoint, but showing a relative difference of position of some of said parts; and Fig. 8, Sheet 1, a modification, all hereinafter fully specified. Fig. 9 is a detail view of the tripping device.

A, Fig. 1, is an ordinary reel-rake cam of a grain-harvester, having the usual switch, k, shown in plan.

B is a body-piece or body of my tripping device, held to and beneath the cam by a bolt, n, at a point about ninety degrees around the cam from the switch.

w is an arm rigidly attached to the lower end of the switch shaft or gudgeon b, and has connected with it a tripping-latch, l, which reaches to and passes through a slot in the body B.

d is a hand-lever attached to one side of the body B, and G the upturned end of a trip-arm attached to the other side of the body, mostly obscured by a catch-bar, g, the said trip-arm being operated by the pins of the pin-wheel h,

secured to the rake-shaft C, which will more clearly appear farther on.

In Fig. 4, drawn to a larger scale, the end of the trip-latch l is shown hinged to the extremity of the arm w, which arm is secured to the lower end of the gudgeon b of the switch k, said gudgeon passing down through a boss, D, of the lower web of the cam A. A spring, p, secured to the boss D presses against the arm w in such a manner as to keep the switch constantly open when left to itself, as shown in dotted position in Fig. 1, which causes the trip-latch l to be pushed farther through the body B, also shown in dotted position in said figure.

As shown in Fig. 2, (the parts enlarged being viewed in a direction indicated by the arrow at the bottom of Fig. 1,) the trip-arm f is journaled upon a horizontal pin, t, projecting from the body B at its outer end, so as to allow the trip-arm to have a motion in a vertical plane, its lowermost and uppermost positions being shown, respectively, in full and dotted lines. At its extreme end the arm f is expanded into a head and provided with parallel and equidistant ledges a a' a'', crossing the head obliquely. (Better shown in Fig. 3.) The trip-arm f is held in such relation to the rotating shaft C that the pins c c' c'' c''' of the wheel h may strike into the grooves under the ledges of said trip-arm.

The trip-arm has a shorter arm, G, reaching upward, to which is hinged a horizontal catch-bar, g, which rests at its opposite end in a loop, e. This catch-bar is provided with notches o o' o'', and it is evident that if the head of the trip-arm f be raised the catch-bar g will be carried to the left and drop, so that the successive notches o o' o'' shall rest upon the bottom part of the loop e as the head goes upward. The ledge a being oblique, it is evident that the pin c, striking in under the highest part of said ledge, and being carried horizontally around by the rotation of the shaft C, will lift the trip-arm to the amount of the obliquity of said ledge a, which will cause the catch-bar g to drop, so that the notch o will rest upon the loop e, as above described. The catch-bar having dropped to the first notch, o, the trip-arm f will be prevented falling, by its own weight, to the position it just previously occu-

pied, but will be held so that when the pin c' approaches it will strike fairly under the ledge a' and raise the arm f another degree, which will allow the bar g to drop to the next notch, o' , and again hold the arm f , so that the pin c^2 may strike under the ledge a^2 and lift the arm, as before, allowing the bar g to drop to the third notch, o^2 .

y is a slide-bar fitted to lie upon the under side of the arm f , to which it is attached by screws $z z$, passing through longitudinal slots in the said slide-bar and entering the arm. This slide-bar is provided at its end with a ledge, a^3 , similar to the ledges $a a' a^2$, and forming an equal one of the series of four ledges.

When the pin c^2 has passed under the ledge a^2 , as above described, and the bar g has dropped to the notch o^2 , the ledge a^3 will be in position for the next pin, c^3 , (diametrically opposite to pin c'), by means of which the arm f will be raised a fourth time.

As shown in Fig. 3, the trip-latch l passes through a slot, m , in the body B , and at its end is provided with an inclined surface, i , and a shoulder, r .

Observing Fig. 1, when the switch h is closed, as shown in full lines, and the trip-latch l in consequence drawn in a direction away from the body B , the shoulder r of the latch will drop down by the side of the body at the lower end of the slot m and lock the switch shut, as against the effort of the spring p to open it, as above described.

Should the trip-latch by any means be raised so the shoulder r may enter the slot and be relieved from the pressure against the side of the body B , the spring p will instantly drive the trip-latch through the slot m and throw the switch open.

In moving upward, as above described, the trip-arm f raises the trip-latch and allows the spring p to throw the switch open.

As shown in Fig. 2, the normal position of the arm f is some distance below the trip-latch l , which latter, in its lower or locking position, is shown in dotted lines.

After the pins $c c' c^2$ of the wheel h have successively passed under the respective ledges $a a' a^2$, as above stated, the trip-arm will be raised up to the under edge of the trip-latch, the relative position of which parts at this stage of the operation being shown in Fig. 7, Sheet 2, the catch-bar g having dropped so that the extended part x above the notch o^2 rests upon the loop e . Now, when the fourth pin, c^3 , passes under the fourth ledge, a^3 , the arm f will be raised sufficiently to lift the trip-latch l up into the slot m , and the switch will be immediately opened and allow the nearest approaching rake to pass in and rake the platform.

As the latch l is driven into the slot m by the spring, the inclined surface i crowds under the catch-bar g and lifts it off the lower portion of the loop e , which permits the arm f to fall, by its own weight, to its normal position, (shown in full lines in Fig. 2), and ready to be

again carried upward by means of the pins of the wheel h , as above described.

When the roller of the rake which clears the platform passes within the switch, it closes the switch, in the usual way, by pressing against the short arm v , the closing of which causes the shoulder r of the latch l to drop by the side of the body B and lock the switch shut until opened in the manner above described.

It will be observed, in the above-described operation of the arm f , that up to the time the pin c^2 has passed under the ledge a^2 the switch has not been affected, and nothing has been accomplished, save that the arm f has been brought to a position such that the next pin c^3 may open the switch, as stated. Consequently, if the ledge a^3 were lacking, the latch l would not be tripped, and the switch would remain permanently closed.

The slide-bar y , forming at its end the ledge a^3 , and held to the arm f by screws $z z$, passing through slots $u u$, is designed to be slid longitudinally to the left, as shown in dotted position in Fig. 2, far enough to permit the said ledge a^3 to escape the pin c^3 , the said slide-bar being shown in this new position in full lines in Fig. 7.

After the ledge a^2 has been raised above the plane of the pins they pass under said ledge without effecting anything, and the switch remaining closed the rakes act only as reels for the grain until the ledge a^3 is again brought into place in the series, when the latch will be immediately tripped and the platform raked by one rake. The number of pins or projections $c c', &c.$, must correspond with the number of rakes the harvester is provided with.

A hand-lever, d , Figs. 2 and 5, is held by a bolt, j , to the body B on the opposite side from the trip-arm f , said lever also resting at another point in a corrugated lever-rest, F , as shown in Fig. 6. When at its lowest position the lever rests upon a shoulder or ledge, b' , of said lever-rest F .

The trip arm or bar f is provided with a stop-pin, s , which reaches horizontally through under the body B , and, resting upon the lever d , as shown, forms a stop for the descent of said trip-arm.

The bottom notch, e' , of the lever-rest F is relatively so arranged that when the lever d rests therein the stop-pin s , resting upon said lever, holds the arm f in such position that the ledge or projection a will be acted upon by a pin or projection of the wheel h , as above described.

Should the lever be raised to the notch e' of the lever-rest F , the trip-arm will be held so that the ledge a' will be acted upon by a pin or projection of the wheel h , the ledge a not being brought into use.

If the lever be adjusted to the notch e^3 , the ledge a^2 will receive the first pin of the wheel h , the two ledges above not being acted upon; and if said lever be placed in the notch e^4 , the ledge a^3 will receive all the pins or projections of the wheel h as they come around.

Every time a projection of the wheel h acts upon the ledge a^3 the latch l is tripped, the switch opened, and the platform raked, which occurs only when said ledge is acted upon.

5 If the arm f be at its lowest position, as shown in Fig. 2, three pins must pass the ledges before the ledge a^3 is reached and a rake permitted to clear the platform.

If the lever be adjusted to the notch e^2 , as 10 above, every third pin will act upon the ledge a^3 and every third rake clear the platform, and if placed in notch e^3 every second rake will clear the platform, which will be raked by each 15 rake as it comes around, if the lever be raised to notch e^4 .

From the foregoing explanation of the working of the various parts of the device it will be understood, first, that if the slide-bar y be drawn back the rakes will only reel the grain 20 onto the platform; secondly, if said slide-bar be replaced and the stop-lever d raised to the notch e^4 , every rake will clear the platform and the grain will be swathed; and, thirdly, by placing the lever in other notches of the 25 lever-rest F , every second, third, or fourth rake may be caused to rake the platform, as desired.

The slide-bar y is provided with a curved slot, g' , and a pin, h' , reaches from the lever 30 d into said slot, by means of which the said slide-bar may be operated by said hand-lever d , the latter being slotted where the bolt j passes through it to allow of sufficient end-wise motion for the purpose.

35 A spring, h' , Fig. 3, under the head of the bolt j , presses against a washer, r' , to hold the lever d snugly against the side of the body B , but at the same time will admit of the lever being sprung sufficiently back from the body 40 to be adjusted to the notches of the lever-rest F .

An equivalent of the ledges a a' a^2 a^3 and the pins c c' c^2 c^3 , as shown, would be to put the ledges on the periphery of the wheel h in 45 the form of spiral inclines, and the pins in the head of the trip-arm f in the place of the ledges—a manner of construction I may wish to adopt.

In Fig. 8 is shown a pendent catch-bar, s' , provided with notches to receive and hold the pin x' of the trip-arm f as the latter is carried 50 successively upward, as hereinbefore described.

A spring, v' , holds the bar against the pin in the various positions of the latter, and the 55 inclined plane of the latch l , corresponding to the inclined plane i , above described, extends out laterally toward the bar s' , as shown by dotted lines at n' , so that when the latch l is driven through the slot m by the spring p , as 60 above described, said plane n' will throw the bar s' back, as shown in dotted position, and release the pin x' to allow the arm f to drop.

Fig. 9, Sheet 2, shows the tripping device as being adapted to be directly operated by 65 the rakes instead of by the wheel h , as above set forth.

A is a sectioned portion of the rake-cam; E,

a portion of a rake having the usual roller, s^2 , to traverse the cam. The stems or pins c^4 of the several rakes, upon which the rollers s^2 70 turn, extend beyond the ends of said rollers sufficiently to operate the trip-arm f , as above described, said pins c^4 of the rakes taking the place of the pins c c' c^2 c^3 of the wheel h .

I disclaim, first, in a tripping mechanism, the 75 combination, with the latch or part to be tripped, of a pivoted tripping-arm, an actuator for moving the tripping-arm in one direction step by step, to trip the latch or part to be tripped, and means for preventing a return movement 80 of the tripping-arm while being operated upon by the actuator; second, in a tripping mechanism, the combination, with a latch or part to be tripped, of a pivoted tripping-arm, an actuator for moving the tripping-arm in one direction step by step, to trip the latch or part to be 85 tripped, means for preventing the return movement of the tripping-arm while being operated upon by the actuator, and means for returning the tripping-arm to its normal or first position 90 after being released from the detaining means; third, in a tripping mechanism, the combination, with the latch or part to be tripped, of a pivoted tripping-arm, an actuator for moving the tripping arm in one direction, to trip the 95 latch or part to be tripped, means for preventing the return movement of the tripping-arm while being operated upon by the actuator, a means for returning the tripping-arm to its normal or first position after being released 100 from its detaining device, and means for automatically releasing the tripping-arm from the detaining device as the latch or part is tripped; fourth, the combination of the pivoted tripping-arm, its means for returning it, and a stop 105 for arresting its return movement; fifth, the combination of the pivoted tripping-arm, its means for returning it, the adjustable stop-arm, the lever on which the stop is mounted, and a means for locking the lever in different 110 positions; sixth, the combination of a latch, a reciprocating pivoted tripping-arm, means for moving the tripping-arm in one direction to trip the latch, and means for moving it in the opposite direction to return it to its first 115 or normal position after tripping the latch; seventh, the combination of a latch, a reciprocating pivoted tripping-arm, an actuator for moving the tripping-arm in one direction step by step, to trip the latch, and means for returning the tripping-arm to its normal or first 120 position. I am not the first inventor of the foregoing.

I claim as my invention—

1. A catch-bar, g , and trip-arm f , with suitable means to operate the latter, in combination with a trip-latch, l , provided with an inclined plane, i , for the purpose set forth. 125

2. In combination, the rake-cam A and rake-shaft C of a grain-harvester, with the slotted body B , trip-arm f , trip-latch l , catch-bar g , and wheel h , substantially as set forth. 130

3. The combination, with the body B and trip-arm f , substantially as shown, of the slide-

bar y , provided with a ledge, a^3 , and curved slot g' , and a lever, d , provided with a pin, h' , entering said slot, for the purpose set forth.

4. In combination with the body B and trip-arm f , with its stop-pin s , a stop-lever, d , and corrugated lever-rest F , substantially as described and shown.

5. In combination with the trip-arm f , provided with ledges $a a' a^2 a^3$, and stop-pin s , and device h , for operating said trip-arm, an adjustable stopping device, d , by means of which the trip-arm may be held, so that a part or all of said ledges may be acted upon by the said device h , as described.

15 6. In combination with the shaft C and pin-

wheel h , an arm or bar, f , provided with a series of ledges or projections, $a a' a^2 a^3$, one of which is removable from the series, substantially as described and shown.

7. In combination with the rake-shaft C of 20 a grain-harvester, a wheel, h , provided with projections $c c' c^2 c^3$, an arm, f , provided with projections $a a' a^2 a^3$, and catch-bar g , with a loop or catch, e , for the latter, substantially as shown.

FRANCIS W. RANDALL.
